GEORGE A. SEIB, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,243,451.

Specification of Letters Patent. Patented Oct. 16, 1917.

Application filed October 4, 1916. Serial No. 128,656.

To all whom it may concern:

Be it known that I, GEORGE A. SEIB, citizen of the United States, and resident of Ilion, in the county of Herkimer and State 5 of New York, have invented certain new and useful Improvements in Type-Writing Machines, of which the following is a specification.

My present invention relates to carriage 10 feeding devices for typewriting machines and its general object is to provide new and improved devices of the character specified. More specifically my invention relates to novel escapement mechanism employing a 15 reed or tongue dog or dogs in place of the usual escapement embodying a pivoted or slidably mounted dog which requires accurate fitting to insure an evenly timed let-off.

To the above and other ends my present 20 invention resides in the features of construction, combinations of devices and arrangements of parts hereinafter described and particularly pointed out in the claims.

In the accompanying drawings which 25 illustrate one form of my invention applied to a No. 11 Remington front-strike typewriting machine,

Figure 1 is a fragmentary front to rear vertical sectional view of said machine.

30 Figs. 2 and 3 are respectively a side elevation and a rear elevation partly in section of the escapement devices.

Fig. 4 is a horizontal sectional view taken 35 on a plane indicated by the dotted line $x-x$ in Fig. 3, said figure being drawn to an enlarged scale.

Fig. 5 is a horizontal sectional view taken 40 on a plane indicated by the dotted line $y-y$ in Fig. 3.

Figs. 6 and 7 are respectively a fragmentary side elevation and rear elevation, drawn 45 to an enlarged scale and showing the escapement devices in operated positions.

Fig. 8 is a fragmentary view of a modification.

As appears from Fig. 1, the main frame 50 of the Remington front-strike typewriting machine comprises a base 1, uprights 2 and a top plate 3, above which are fixed grooved guide rails 4 and 5 that coöperate 55 through anti-friction balls 6 with the grooved front and rear bars 7 and 8 of a carriage truck that also comprises end bars 9, said truck being part of a traveling carriage 60 in which is mounted a rotary platen

10. Coöperative with the front face of the platen are type bars 11 mounted on hangers 12 secured to the stationary support or segment 13, the type bars being each actuated by a train of devices comprising a link 14, 60 lever 15, and a second link 16, which latter is connected to a key lever 17, the key levers being fulcrumed on a bar 18 fixed to the rear of the base and each being provided with a restoring spring 19 and a key cap or button 65 20. Outside the set of key levers are a pair of parallel spacing levers 21 which are also fulcrumed on the bar 18 at the rear and are connected at their front ends by a space bar 22. Each lever 21 is provided with an enlargement 23 formed with a guide slot 24 for the reception of a universal bar 25 that underlies the key levers and is adapted to be actuated by each one of them. The universal bar is supported by links or arms 70 26 pivoted at their upper ends at 27 to arms 28 extending rearward from a rock shaft 29 pivoted in the sides of the base. Fixed centrally to the rock shaft and extending rearward therefrom is an arm 30 formed 80 with a hook end, the slot 30^a wherein receives a pin 31 fixed to the lower end of a diagonally arranged link 32, the upper end whereof is pivotally connected to the forwardly extending arm 33 of a rocker that 85 further comprises an upwardly extending arm 34 and a hub 35 (Fig. 3) in which is fitted a shaft or spindle 36 having coned ends that coöperate with bearing pins 37 secured in lugs 38 projecting rearward from 90 a bracket 39 that is fixed to and depends from the top plate. A screw 40 extending upward through the hub 35 secures it and the shaft 36 in fixed relationship and also provides a connection for a coiled restoring 95 spring 41 that has its rear end hooked around the grooved head of the screw, the forward end of said spring being anchored to an arm 42 fixed to the bracket 39. The rocker arm 33 has also pivoted to it behind 100 the link 32 a second link 43, the lower end of which is slidably supported in a cross rod 44 fixed at its ends to the enlargements 23. A nut 45 threaded on the lower end of the link 43 below the rod 44 provides an 105 abutment against which said rod acts when the space bar 22 is depressed, the result being that the link 43 is caused to operate the rocker comprising the arm 33. During such operation it will be understood that the pin 110

31 slides downward in the slot 30^a with the result that the rock shaft 29 and universal bar 25 are not affected. It will further be apparent that when one of the printing keys 5 20 is actuated; causing the connected type bar 11 to print and also depressing the universal bar 25, motion will be transmitted through the rock shaft 29, arm 30 and link 32 to the rocker arm 33, actuating the rocker 10 and depressing the link 43 which, however, will slide through the rod 44 without affecting the space levers and bar. Most of the parts thus far described are, or may be, like the corresponding parts in the No. 11 Remington machine except for the rocker 33—36. 15 This rocker, instead of being a dog carrier, as in the regular construction, operates as a dog actuator, the dogs proper being of a novel construction and mounted on a stationary part of the machine. Said dogs, 20 presently to be described, coöperate in the present showing with a double wheel of ordinary construction, said wheel comprising a rear wheel 46 provided with teeth 47 and a front wheel 48 provided with teeth 49, the said front and rear wheels being adjustably secured together by devices comprising screws 50 so as to give a drop of any desired extent from the teeth of the front 25 wheel to the teeth of the rear wheel. The double escapement wheel, comprising the single wheels 46 and 48, is mounted on a horizontal shaft 51 which bears in a bracket 52 fixed to the top plate. Said shaft has 30 fixed to its forward end a feed pinion 53 with which normally meshes a spring pressed feed rack 54 carried by arms 55 pivoted at 56 to lugs on the rear bar 8 of the traveling carriage. The usual spring drum 40 (not shown) tends constantly to draw the traveling carriage leftward across the machine.

Referring to the novel dog devices, in the present instance a piece 57 of spring tempered sheet metal is divided by a slot 58 (Fig. 5) into two flexible or resilient tongues, reeds or dogs 59 and 60 which are adapted for coöperation respectively with the teeth 49 and 47 of the double escapement wheel. The dog plate or member 57 is formed with an elongated slot or hole 61 which receives a screw 62 by which it is adjustably secured to a support or block 63. Said block is bored out, as indicated at 64, 55 and slotted, so that in effect it is U-shaped, having when viewed from the rear as in Fig. 3, a right-hand upstanding arm or branch 65 and a left-hand branch 66. The branch 65 receives on its top face the dog 60 piece 57 which is secured in place by the screw 62 and thence extends horizontally inward toward the teeth of the escapement wheel. In other words, the dogs including their working portions are arranged substantially tangentially to the teeth of the

wheel which rotates in a vertical plane. The branch 66 is fitted to the under side of the top plate 3 and is secured thereto by headed screws 67 which pass downward through the top plate and are threaded into holes in the 70 enlarged upper end of the arm or branch 66. The reason for giving the block or support 63 the shape shown and which is conveniently described as split or U-shaped, is that it affords a slight resilient or spring action 75 under the impact of the blow of the escapement wheel teeth against the ends of the spring dogs, as hereinbefore described, and this tends to reduce somewhat the noise. The dogs 59 and 60 are controlled by actuators or links which provide a connection between said dogs and the rocker 33—36. 80 There are two of these actuators or operating connections 68 and 69 vertically arranged one behind the other. These actuators are similar in construction, each being formed of a flat piece of metal provided at its upper end with a head, twisted at right angles to the body, that of the forward actuator being numbered 70 and that of the 85 rear 71. The heads 70 and 71 pass through slots 72 and 73 formed in enlarged portions of the respective dogs 59 and 60 about midway of their lengths, and then said heads are given a quarter turn so that they are at right 90 angles to the slots, as best shown in Fig. 5, the construction providing against accidental disconnection. The lower ends of the respective actuators are formed with somewhat larger heads 74 and 75 which 95 pass through slots 76 formed in the attaching piece or plate 77 that is mounted on top of the dog rocker and has an inverted U-portion 78 curving around or embracing the arm 34 and being secured in place by a 100 headed screw 79 threaded into said arm. The arm 34 receives near its upper end a forwardly extending adjustable screw 80 which coöperates with an abutment 81 on the bracket 89 to limit forward swings of 110 the rocker. The piece 77 is additionally secured by the screw 40 which projects upward through both the hub 35 and the horizontal portion of the piece 77 and receives two locking nuts 82 by which said piece is 115 clamped to the rocker. The tongue 59 is in the plane of the wheel 48 and the tongue 60 is in the plane of the wheel 46, and the arrangement of the tongues is such that moving up and down in these planes and at 120 right angles to the movement of the rocker they coöperate with the teeth of these respective wheels under the axis of the shaft 51. The horizontal plane that contains the two tongues cuts into the lowermost teeth 125 of the wheels near their tips. The spring tension of the tongues is such that they tend to spring back to the horizontal plane after having been flexed to permit the teeth of the escapement wheels to escape or move past. 130

The flexing or bending of the tongues is controlled by the actuators 68 and 69. It will be understood from Figs. 2 and 5 that the forward actuator 68 is in front of the vertical plane, passing through the axis of the rocker spindle 36, while the rear actuator 69 is behind said plane. Consequently it will be understood that when the rocker is rocked forward by the actuation of one of the printing keys or the space key, the actuator 68 will swing or move downward while the actuator 69 will move correspondingly upward, the reverse movements taking place on the return of the dog rocker after the printing operation. Normally the tongue 59 is engaged with the lowermost tooth 49 of the front set of teeth, as shown clearly in Figs. 3 and 5. At this time the tongue 60 is flexed downward so that it is out of the path of the teeth 47 of the rear set of teeth. When the rocker is rocked forward the actuator 68 is lowered and will draw down or flex the tongue 59 so that it will slide down off the tip of the tooth 49, permitting the double escapement wheel to rotate and advance the carriage toward the left under the pull of the spring drum. At the same time that the actuator 68 moves downward the actuator 69 moves upward and thus permits the flexed tongue 60 to rise through its inherent spring tension until it is in the path of a tooth 47, the result being that the proximate tooth 47 just back of the released tooth 49 will coöperate with the end of the tongue 60 to arrest the escapement wheel and the carriage. In other words, the forward swing of the dog rocker or reciprocating member under the actuation of the printing key permits the usual drop to take place, this drop being measured by the distance between any two associate teeth 49 and 47 of the double escapement wheel. The position of the parts at this time is illustrated in Figs. 6 and 7 which show the dog rocker swung forward and the rear tongue 60 horizontal and in engagement with the wheel tooth 47, the tongue 59 being flexed downward out of the path of the wheel tooth 49. On the release of the printing key and the return of the dog rocker to normal position, the actuator 69, swinging downwardly, will bend the tongue 60 downward, causing it to release the engaged tooth 47 and permitting the double escapement wheel to turn. At the same time the actuator 68 will move upward, permitting the flexed tongue 59 to return to the horizontal plane in position to arrest the escapement wheels and the carriage by reason of the engagement of the end of the tongue 59 with the tooth 49 next behind that with which the tongue had coöperated prior to the beginning of the escapement operation. The above described operation is repeated at each actuation of the printing key, resulting in the bending

or flexure of the two spring tongues in alternation, and consequent movement of their ends radially of the escapement wheel to permit a letter space movement of the carriage.

It may be remarked that the engaged tongue or leg 59 of the dog or pawl member 57 acts as a ratchet during return movements of the carriage and escapement wheel or rack, being swung downward or flexed by the backs of successive wheel teeth 49.

As stated, the principal idea of the present invention was to do away with the usual movable dog which, whether it swings on a pivot or slides, requires accurate fitting to secure an evenly timed "let off," such fitting being both difficult to attain and also expensive. The substituted reed or tongue dog or pawl, as described, embodies two tongues which coöperate at their points or free ends with the teeth of the double wheel, the tongues being even at the contact point and the drop being obtained from the two sets of teeth on the wheel or in other words by setting the two toothed parts of the double wheel so that the teeth of one set are more or less behind those of the other. Obviously, however, another style of toothed member or rack such for example as a single wheel or, otherwise expressed, a single set of teeth, may be used, such as is illustrated in Fig. 8 and marked 83. This wheel coöperates with two spring tongues or dogs 84 and 85 of different lengths, the normally disengaged tongue 85 being shorter than the other so that when the tongue 84 is flexed downward and the tongue 85 returns to the horizontal, the consequent drop will carry the engaged wheel tooth past the end of the dog 84; consequently said dog will coöperate with the next succeeding wheel tooth when the dog rocker returns to normal position. Other constructional modifications will readily suggest themselves.

Various changes may be made without departing from my invention.

What I claim as new and desire to secure by Letters Patent, is:

1. In carriage feeding devices for typewriting machines, the combination of a key controlled reciprocating member, a toothed rack, and a flexible tongue coöperating with said rack, said tongue being supported independently of but being controlled by said reciprocating member.

2. In carriage feeding devices for typewriting machines the combination of a key controlled rocker, an escapement wheel, a flexible tongue coöperating with said wheel and an operating connection between said tongue and said rocker through which said rocker controls said tongue.

3. In carriage feeding devices for typewriting machines, the combination of a key controlled rocker, an escapement wheel, and

- a pair of flexible tongues coöperating with said wheel, said tongues being controlled by said rocker.
4. In carriage feeding devices for type-writing machines, the combination of a key controlled reciprocating member, a rack, and a flexible dog mounted on a stationary part and coöperating with said rack, said dog being controlled by said member.
5. In carriage feeding devices for type-writing machines, the combination of a key controlled reciprocating member, a rack, and a pair of flexible dogs mounted on a stationary part and operative by said member to alternately coöperate with said rack.
6. In carriage feeding devices for type-writing machines, the combination of a key controlled rocker, an escapement wheel, and a flexible dog mounted on a stationary part and coöperating with said wheel, said dog being controlled by said rocker.
7. In carriage feeding devices for type-writing machines, the combination of a key controlled rocker, an escapement wheel, and a pair of flexible dogs mounted on a stationary part and coöperating with said wheel, said dogs being controlled by said rocker.
8. In carriage feeding devices for type-writing machines, the combination of a key controlled rocker, an escapement wheel, and a yielding dog mounted independently of said rocker and coöperative with said escapement wheel, said dog being controlled by said rocker.
9. In carriage feeding devices for type-writing machines, the combination of a key controlled rocker, an escapement wheel, and a pair of yielding dogs both mounted independently of said rocker but controlled by said rocker to coöperate alternately with said escapement wheel.
10. In carriage feeding devices for type-writing machines, the combination of a toothed rack, a key controlled reciprocating member movable transversely of said rack, and a dog mounted independently of said member but controlled thereby and coöperating with said rack, said dog having movement in the plane of said rack.
11. In carriage feeding devices for type-writing machines, the combination of a toothed rack, a key controlled rocker movable transversely of said rack, and a dog mounted independently of said rocker but controlled thereby, said dog having a movement in and out of said rack in the plane of said rack.
12. In carriage feeding devices for type-writing machines, the combination of an escapement wheel, a key controlled rocker movable transversely of said wheel, and a dog normally engaged with said wheel and movable by said rocker radially of said wheel to release the same.
13. In carriage feeding devices for type-writing machines, the combination of an escapement wheel, a key controlled rocker movable transversely of said wheel, and a dog or pawl having its point normally engaged with a tooth of said wheel and movable by said rocker so that said point rides outward radially of said tooth and past its end to release the wheel.
14. In carriage feeding devices for type-writing machines, the combination of a key controlled reciprocating member, a rack, and a flexible tongue coöperating with said rack, said tongue being flexed by said reciprocating member during movements of the carriage in printing direction and being flexed also by the teeth of said rack during movements of the carriage in return direction.
15. In carriage feeding devices for type-writing machines, the combination of a key controlled rocker, an escapement wheel, and a flexible tongue coöperating with said wheel, said tongue being flexed by operating said rocker during movements of the carriage in printing direction and being flexed by the teeth of said wheel during return movements of the carriage.
16. In carriage feeding devices for type-writing machines, the combination of a circular rack, a key controlled member reciprocating in a plane at right angles to said rack, and two dogs controlled by said member and yieldable at right angles to the movement thereof, the working portions of said dogs being normally arranged substantially tangentially of said circular rack.
17. In carriage feeding devices for type-writing machines, the combination of a rack, a reciprocating member movable transversely of said rack, and two dogs alternately movable in the plane of said rack and into and out of engagement therewith, said dogs being controlled by said reciprocating member.
18. In carriage feeding devices for type-writing machines, the combination of an escapement wheel provided with two sets of teeth, and a pair of key controlled reed dogs, one coöperative with each of said sets of teeth.
19. In carriage feeding devices for type-writing machines, the combination of an escapement wheel provided with two sets of teeth, a pair of reed dogs, one coöperative with each of said sets of teeth, and key controlled means for alternately flexing said dogs.
20. In carriage feeding devices for type-writing machines, the combination of a toothed rack, a flexible dog against the end of which said teeth are adapted to successively abut, and key controlled means for flexing said dog.
21. In carriage feeding devices for type-writing machines, the combination of a

toothed member, a pair of flexible dogs against the ends of which said teeth are adapted to abut, and means for alternately flexing said dogs to permit of the escapement of said teeth successively.

22. In carriage feeding devices for typewriting machines, the combination of a toothed rack, a resilient support, a flexible dog on said support, and key controlled means for flexing said dog.

23. In carriage feeding devices for typewriting machines, the combination of a toothed rack, a resilient support, a flexible dog on said support, and key controlled means for flexing said dog, the teeth abutting successively against the end of said dog.

24. In carriage feeding devices for typewriting machines, the combination of a toothed rack, a resilient U-shaped support, a dog secured to one of the branches of said support, the other branch of said support being fixed to a stationary part of the machine, and key actuated means for controlling said dog.

25. In carriage feeding devices for typewriting machines, the combination of a toothed rack, a rocker below said rack, a pair of dogs mounted independently of said rocker and coöperative with the teeth of said rack above said rocker, and two connections, one for each dog to said rocker, said connections being at opposite sides of a vertical plane passing through the axis of said rocker.

35 26. In carriage feeding devices for typewriting machines, the combination of a toothed rack, a pair of horizontally arranged flexible dogs against the ends of which the teeth of said rack are adapted to abut, a key controlled rocker arranged below said dogs, and links connecting said dogs with said rocker, said links being on opposite sides of a vertical plane passing through the axis of said rocker.

45 27. In carriage feeding devices for typewriting machines, the combination of an escapement wheel provided with two sets of teeth, two flexible spring tongued dogs screwed to a stationary part and coöperative in alternation with the sets of teeth, one dog with each set, a key controlled rocker, and two arms or links connecting said rocker with said dogs, the links being so arranged

that they move in opposite directions when the rocker is actuated.

28. In carriage feeding devices for typewriting machines, the combination of a key controlled rocker, an escapement rack, a pair of flexible tongues coöperating with the teeth of said rack, and a pair of links connecting said rocker with said tongues and arranged so that they move in opposite directions when the rocker is actuated.

29. In a typewriting machine and escapement mechanism comprising in combination a toothed wheel, a pair of dogs arranged substantially tangential to the teeth of said wheel alternately to abut said teeth, and means for actuating said dogs.

30. In a typewriting machine and escapement mechanism comprising in combination a toothed wheel, a pair of flexible dogs constructed and arranged so that their free ends alternately abut the teeth of said wheel, and means for actuating said dogs.

31. In a typewriting machine, the combination with an escapement wheel, of a resilient plate divided to provide two substantially parallel spring dogs for coöperation with the teeth of said wheel in substantially the manner specified.

32. In carriage feeding devices for typewriting machines, the combination of an escapement wheel, a horizontally arranged dog, the working portion whereof is normally disposed substantially tangentially of said wheel, and key controlled means for moving the working portion of said dog radially of said wheel.

33. In carriage feeding devices for typewriting machines, the combination of an escapement wheel having two sets of teeth, a pair of horizontally arranged dogs extending under said wheel and having their working portions normally disposed substantially tangentially of said wheel, and key controlled means for moving the working portions of said dogs substantially radially of said wheel.

Signed at Ilion, in the county of Herkimer, and State of New York this 2nd day of October A. D. 1916.

GEORGE A. SEIB.
